Fig. 1

Fig. 3

Figure 1 is a front view of a golf putter head, showing my new design.

Fig. 2 is an end elevation of Fig. 1.

Fig. 3 is a top view of the golf putter head of Fig. 1.

The design of the present invention is characterized by the target area of the striking face being relatively short and disposed closely adjacent the hosel of the club and the hosel extending upwardly from the club at a relatively sharp angle, all as shown.

I claim:

The ornamental design for a golf putter head, as shown and described.
